COIN-FREED MACHINE

Percy Stephen Harper, Croydon, England

Application June 13, 1935, Serial No. 26,444
In Great Britain November 19, 1934

5 Claims. (Cl. 194—97)

This invention has reference to coin selecting and testing mechanism, such as is used in coin-free vending machines, of the type wherein thickness, diameter, magnetic and/or other properties of a coin are checked by the aid of a runway associated with various gauge devices and the like and including a pivoted side wall or frame to the runway which can be opened to release inappropriate coins or discs which may have been held up in the runway, so that they may be thrown out or fall out into a rejected coin chute.

It is the usual practice for the said pivoted side wall to be interconnected with the drawer mechanism or with a "return coin" button, or other device, whereby, following the insertion of the coin, a subsequent manual operation will lift the side wall and bring about the discharge of any rejected coin. It has been proposed, however, to perform the lifting operation automatically after a requisite time interval following coin insertion, so that should a coin or disc be held up in the testing mechanism it will be automatically returned as rejected without further effort on the part of the operator.

The present invention is concerned solely with an improved delay action device for automatically lifting the pivoted side wall. The actual construction and nature of the gauges employed form no part of the invention, it merely being essential to the invention that the testing and selecting mechanism shall be broadly of the type herein defined, of which many varied constructions are well known in the art.

According to the invention, the pivoted side wall is held in a normally open position by means of a pivoted lever loaded by means of a spring, weight or equivalent, and said lever is movable to release and close the wall by the act of inserting a coin, means being applied to the lever to delay its return under the influence of the spring or the like, and thus to delay also the re-opening of the side wall, the last named action being consequently automatic. Preferably, the pivoted lever is a spring loaded bell-crank one arm of which carries a coin thrust part, located behind the coin slot and controlling the movement of a tongue projecting from the pivoted wall, the other arm being governed by a suitable mechanical delay action or check device which is advantageously a form of escapement action.

An embodiment of the invention is illustrated in the accompanying drawing by way of example.

Figure 1 is a front elevation of coin testing mechanism embodying the invention.

Figure 2 is a side elevation viewed from the left of Figure 1.

Figure 3 is a side elevation viewed from the right of Figure 1.

Figure 4 is a detail view to be referred to later.

Referring to the drawing, B indicates in a general manner the stationary parts of the apparatus which are rigidly secured to the casing of a vending machine or other device to which the coin selecting and testing mechanism is applied, and A indicates in a similar manner the movable wall and associated devices.

The movable wall 1 which is adapted to complete the coin runway when in its closed position and carries various coin gauging and testing devices 2, 3, 4 with which the invention is not further concerned, is pivoted by pin 5 to a stationary wall 6 which includes the rejected coin chute 7 and is adapted to be secured in the frame of an automatic vending machine or the like by means of screw bolts 8 fitted to the coin shield 9 wherein is formed a coin slot 10.

Pivotedly mounted on the stationary wall 6 at 11 is a bell crank lever 12, 13 the arm 12 whereof is continuously pulled downwards by a spring 14 anchored to the stationary wall 6 by one of its ends at 15.

The pivoted side wall 1 has a projecting tongue 16 which engages under the arm 12 of the bell crank lever 12, 13 and is pulled downwards thereby, with the result that the side wall 1 is normally swung out around its pin 5 and is held in open position.

When inserting a coin into the slot 10 it is necessary to close the side wall 1 in order to complete the runway for the coin. This may be accomplished by lifting the arm 12 of the bell crank lever 12, 13 thereby allowing the tongue 16 of wall 1 to rise and the wall itself to close under gravity action, it being noted that the position of both walls 6 and 1 is inclined to the vertical, so that once released the wall 1 closes at once against the wall 6, thus completing the coin runway.

The lifting arrangement for arm 12 of the bell crank comprises a coin thrust member or projection 17 depending from arm 12 and located behind the coin slot 10. When a coin is inserted the thrust member 17 is pushed upwards thereby with the result that the arm 12 is lifted and the side wall 1 closes as aforesaid.

It is obvious that as soon as the coin has passed the thrust member 17 same would be able to move downwards with arm 12 under the action of spring 14, whereby side wall 1 would be again 55

opened, and this would occur prior to a genuine coin having had time to reach the end of the runway, and thus all coins, genuine or spurious, would fall into the rejected coin chute 7.

5 To prevent this too early opening of the side wall it is necessary to provide a delay action which will retard the opening of the pivoted side wall for such length of time as is required for the coin to pass the full length of the runway.

10 As aforesaid, the invention is concerned with this delay action only, which will now be described.

The delay action according to the invention is mechanical and of the escapement type. It includes a pendulum 18 pivotally mounted on the 15 stationary wall 6 at 19 and carrying a rack 20 adapted to cooperate with a pair of pawls 21 mounted at the lower end of arm 13 of the bell crank lever 12, 13. The pawls are spring pressed as shown in Figure 2 and can rock clockwise only 20 against the action of their springs 22.

The escapement action may best be understood by reference to Figure 2. In this the mechanism is shown in its inoperative position. When a coin is inserted into the slot 10 the thrust member 17 is lifted by the coin as aforesaid and the bell crank lever is rocked. The arm 12 rises and allows the pivoted side wall 1 to close and the arm 13 rocks anticlockwise. In so doing its pawls 21 ride over the rack 20 and the pawl on the right 25 engages with the first tooth of the rack on the extreme right. The spring 14 tends to rock the bell crank lever 12, 13 clockwise but has to do so against the resistance of the pendulum 18 which tends to swing anticlockwise. The spring 30 14 is strong enough to overcome the resistance of the pendulum and thus the pawl on the right which at this moment engages with the extreme right tooth of the pendulum rack rocks the pendulum around its pivot 19 clockwise. The pawl 35 on the right then slips off the tooth with which it had just been in engagement, but the arm 13 is not released by the pendulum, inasmuch as at the same moment that the rack releases the pawl on the right the pawl on the left is caught by 40 another tooth of the rack, this action continuing until all the parts return into their initial position shown in Figure 2. The return of the bell crank lever 12, 13 into its position of rest and therewith the return of the pivoted wall 1 into its 45 corresponding open position is thus delayed in the required manner by the escapement action.

The pivot 19 may be duplicated on the other side of the weight 18 by providing a suitable bearing bracket on the stationary part B. This 50 would ensure a smoother operation and better balance for the weight 18.

It is to be understood that it is not absolutely necessary to employ a bell crank lever as a two armed lever, or even a one armed lever may be 55 utilized carrying a suitably disposed coin thrust extension and subject to the action of a suitably placed spring or some other motive force, e. g. a magnet.

I claim:—

60 1. Mechanism of the character described comprising a coin chute having a fixed body portion

and a pivoted side wall constantly urged inwardly to close the chute for passage of a coin therethrough and outwardly swingable to open the chute for release of a coin therefrom, and an escapement mechanism holding said chute side 5 wall normally swung outwardly and movable by the insertion of a coin into the chute to permit said side wall to swing inwardly to its position closing the chute side, said escapement mechanism including means energized and set into operation by the insertion of a coin into the chute to swing said side wall outwardly after the elapse of a predetermined period of time beginning with the insertion of the coin.

2. Mechanism of the character described comprising a coin chute having a fixed body portion and a pivoted side wall constantly urged inwardly to close the chute for passage of a coin therethrough and outwardly swingable to open the chute for release of a coin therefrom, a movable member cooperating with said chute side wall and urged constantly in a direction to swing said side wall outwardly, means whereby the insertion of a coin into the chute moves said member to permit the chute side wall to swing inwardly and immediately releases said member for movement to swing the chute side wall outwardly, and means set into operation by the movement imparted to said member by the insertion of a coin to delay outward swinging movement 30 of the chute side wall to coin releasing position until after the elapse of a predetermined period of time.

3. Mechanism of the character described comprising a coin chute having a fixed body portion 35 and a pivoted side wall constantly urged inwardly to close the chute for passage of a coin therethrough and outwardly swingable to open the chute for release of a coin therefrom, an intermediate pivoted lever having one arm thereof 40 cooperating with the pivoted side wall of said chute, a spring cooperating with said lever to urge same constantly in a direction to swing said pivoted side wall outwardly, means whereby the insertion of a coin into the chute swings said lever 45 to permit the chute side wall to swing inwardly and immediately releases said lever for swinging movement by said spring to return the chute side wall to an outwardly swung position, and means set into operation by the movement imparted to 50 said lever by the insertion of a coin to delay its movement to swing the chute side wall outwardly to coin releasing position until after the elapse of a predetermined period of time.

4. The combination as set forth in claim 2 in 55 which the means for delaying outward swinging movement of the chute side wall comprises a pendulum and a pawl and ratchet connection between the movable member and said pendulum.

5. The combination as set forth in claim 3 60 in which the means for delaying swinging movement of the lever by the spring to swing the chute side wall outwardly to coin releasing position comprises a pendulum and a pawl and ratchet connection between said lever and said pendulum. 65

PERCY STEPHEN HARPER.
